FIG. 1A

FIG. 1B

FIG. 2

FIG. 3

1

FIRE SUPPRESSION AND ISOLATION SYSTEM

BACKGROUND

Exemplary embodiments pertain to the art of fire suppression systems.

Fire suppression systems may be arranged to deliver a liquid or a dry chemical powder to extinguish or control a hazard such as a fire. In some environments, the hazard may be partially enclosed, such as in a commercial kitchen, making isolation of the hazard from a surrounding space difficult.

BRIEF DESCRIPTION

Disclosed is a fire suppression and isolation system that includes an ejection nozzle, a dispersion nozzle, and a valve assembly. The ejection nozzle is positioned between a non-hazard volume and a hazard volume. The dispersion nozzle is spaced apart from the ejection nozzle and is disposed within the hazard volume. The valve assembly is arranged to control a release of a suppression medium from a container to the ejection nozzle and the dispersion nozzle, responsive to a thermal event, such that the suppression medium ejected from the ejection nozzle defines a fluid barrier that is disposed between the non-hazard volume and the hazard volume.

In addition to one or more of the features described above, or as an alternative to any of the foregoing embodiments, wherein the suppression medium is at least one of water, air, an inert gas, and a clean agent.

In addition to one or more of the features described above, or as an alternative to any of the foregoing embodiments, the dispersion nozzle is arranged to disperse the suppression medium within the hazard volume.

In addition to one or more of the features described above, or as an alternative to any of the foregoing embodiments, the ejection nozzle is at least partially disposed on a workstation that is spaced apart from a hood.

In addition to one or more of the features described above, or as an alternative to any of the foregoing embodiments, a deflector that is spaced apart from and is proximately aligned with the ejection nozzle, the deflector being arranged to deflect at least a portion of the fluid barrier towards the hazard volume.

In addition to one or more of the features described above, or as an alternative to any of the foregoing embodiments, the ejection nozzle is at least partially disposed in a hood that is spaced apart from a workstation.

In addition to one or more of the features described above, or as an alternative to any of the foregoing embodiments, a fluid return having a return inlet that is spaced apart from and is proximately aligned with the ejection nozzle.

In addition to one or more of the features described above, or as an alternative to any of the foregoing embodiments, the fluid return is at least partially defined by the workstation.

In addition to one or more of the features described above, or as an alternative to any of the foregoing embodiments, the fluid return includes a return duct that at least partially extends through the workstation.

Also disclosed is a fire suppression and isolation system that includes an ejection nozzle, a dispersion nozzle, and a container. The ejection nozzle is disposed on at least one of a hood and a workstation. The ejection nozzle is disposed proximate a hazard volume. The dispersion nozzle is spaced apart from the ejection nozzle and extends towards the

2

hazard volume. The container contains a suppression medium and is disposed proximate the hood. The container is fluidly connected to the ejection nozzle and the dispersion nozzle.

5 In addition to one or more of the features described above, or as an alternative to any of the foregoing embodiments, the hazard volume is at least partially defined between the workstation and the hood that is spaced apart from the workstation.

10 In addition to one or more of the features described above, or as an alternative to any of the foregoing embodiments, the ejection nozzle is arranged to eject the suppression medium towards at least one of an edge of the workstation and a front edge of the hood.

15 In addition to one or more of the features described above, or as an alternative to any of the foregoing embodiments, the ejected suppression medium defines a fluid barrier between the hazard volume and a non-hazard volume.

20 In addition to one or more of the features described above, or as an alternative to any of the foregoing embodiments, the fluid barrier is formed as a curtain of laminar flow of the suppression medium.

25 In addition to one or more of the features described above, or as an alternative to any of the foregoing embodiments, the dispersion nozzle is arranged to disperse the suppression medium towards the workstation.

30 In addition to one or more of the features described above, or as an alternative to any of the foregoing embodiments, the fluid barrier is arranged to inhibit the suppression medium from flowing into the non-hazard volume.

35 In addition to one or more of the features described above, or as an alternative to any of the foregoing embodiments, the ejection nozzle is arranged to eject the suppression medium at a first flow rate.

40 In addition to one or more of the features described above, or as an alternative to any of the foregoing embodiments, a fluid return that is spaced apart from and is proximately aligned with the ejection nozzle.

45 In addition to one or more of the features described above, or as an alternative to any of the foregoing embodiments, the fluid return is arranged to receive at least a portion of the suppression medium ejected from the ejected nozzle.

BRIEF DESCRIPTION OF THE DRAWINGS

50 The following descriptions should not be considered limiting in any way. With reference to the accompanying drawings, like elements are numbered alike:

FIG. 1A is a partial view of a first embodiment of a fire suppression and isolation system;

55 FIG. 1B is a partial view of an alternative first embodiment of the fire suppression and isolation system;

FIG. 2 is a partial view of a second embodiment of a fire suppression and isolation system; and

FIG. 3 is a partial view of a third embodiment of a fire suppression and isolation system.

DETAILED DESCRIPTION

60 A detailed description of one or more embodiments of the disclosed apparatus and method are presented herein by way of exemplification and not limitation with reference to the Figures.

Referring to FIGS. 1A-3, a fire suppression and isolation system **10** may be provided in an environment in which a hazard, such as a fire, may occur. The fire suppression and isolation system **10** may be incorporated into a hood **12**, such as an exhaust hood, that is disposed over or disposed proximate a workstation **14**. The workstation **14** may be an appliance, a cooktop, a broiler, a grill, a deep fat fryer, a weld station, a pharmaceutical or biological research station, as well as other appliances or devices in which a fire hazard may be present.

A hazard space or a hazard volume **20** may be at least partially defined between the workstation **14** and the hood **12**. The hazard volume **20** may be area volume or space within which a fire hazard may occur or be present. A work space or a non-hazard volume **22** may be disposed proximate the hazard volume **20**. The non-hazard volume **22** may be a volume containing outside air that may potentially flow towards the hazard volume **20**. The non-hazard volume **20** may be a potentially occupied area in which a worker may be positioned to interface with the workstation **14**. The presence of the worker may inhibit the implementation of a physical barrier or drop down barrier between the hazard volume **20** and the non-hazard volume **22** to separate the hazard volume **20** from the non-hazard volume **22** should there be a fire hazard present within the hazard volume **20**.

The fire suppression and isolation system **10** may be arranged to contain or isolate the hazard volume **20** from the non-hazard volume **22**, as well as suppressing or extinguishing the fire hazard present within the hazard volume **20**. The fire suppression and isolation system **10** may be arranged to inhibit leakage, flow, or ingress of a suppression medium from the hazard volume **20** into the non-hazard volume **22**.

The fire suppression and isolation system **10** may include a container **30**, a valve assembly **32**, an ejection nozzle **34**, and a dispersion nozzle **36**.

The container **30** contains a fluid and/or a suppression medium **38** may be disposed within or disposed proximate the hood **12**. The fluid may be air, water, or the like. The suppression medium **38** may be a fire suppression agent that is at least one of an inert gas or a clean agent. The suppression medium **38** may include but not be limited to: air, carbon dioxide, nitrogen, argon, halon, HFC-125, HFC-227ea, FK-5-1-12, water, a wet chemical extinguishing agent, or a dry chemical extinguishing agent.

The container **30** is fluidly connected to the ejection nozzle **34** and the dispersion nozzle **36** through a series of conduits via the valve assembly **32**. A conduit **40** extends from the container **30** towards a junction **42**. A first branch **44** extends from the junction **42** to the dispersion nozzle **36** and a second branch **46** extends from the junction **42** to the ejection nozzle **34**, as shown in FIGS. 1A and 2.

The conduit **40** may extend from the container **30**, across a portion of the hood **12** towards the first branch **44** that extends from the hood **12** towards the workstation **14**, as shown in FIG. 1B. The second branch **46** may extend from the conduit **40** and may extend from the hood **12** towards the workstation **14** and at least partially across the workstation **14**. A portion of the second branch **46** may extend across the workstation **14** towards the ejection nozzle **34** that is disposed at a forward edge of the workstation **14**. In such an embodiment, the ejection nozzle **34** may eject the suppression medium **38** from the front edge of the workstation **14** towards the hood **12**.

Referring to FIG. 3, a fluid return **50** may be provided that may recycle, recirculate, or return the ejected suppression

medium **38** from the ejection nozzle **34** to inhibit the ejected suppression medium **38** from entering the non-hazard volume **22**.

The fluid return **50** includes a fluid passageway **52**, a duct **54**, and a return duct **56**. The fluid passageway **52** extends from a front edge **60** of the hood **12** across the hood **12** towards the duct **54**. The duct **54** extends between the hood **12** and the workstation **14**. The duct **54** is fluidly connected to the fluid passageway **52** and the return duct **56**. The return duct **56** may extend at least partially through, may extend at least partially across, or may extend at least partially around the workstation **14**. The return duct **56** includes a return vent or a return inlet **70** that is spaced apart from and is proximately aligned with the ejection nozzle **34** and/or the front edge **60** of the hood **12**. The return inlet **70** is disposed proximate an edge **80** of the workstation **14** and may be at least partially defined by the workstation **14** or may be provided as a component that is connected to the workstation **14**. The edge **80** may be a forward edge of the workstation **14**.

In embodiments in which the ejection nozzle **34** is disposed at the workstation **14**, such as in FIG. 1B, the fluid passageway **52** may extend from the edge **80** of the workstation **14** across the workstation **14** towards the duct **54**. The duct **54** may extend between the workstation **14** and the hood **12**. The duct **54** is fluidly connected to the fluid passageway **52** and the return duct **56**. The return duct **56** may extend at least partially through, may extend at least partially across, or may extend at least partially around the hood **12**. The return duct **56** may include a return inlet **70** that is spaced apart from and is proximately aligned with the ejection nozzle **34** and/or the edge **80** of the workstation **14**. The return inlet **70** may be disposed proximate the front edge **60** of the hood **12** and may be at least partially defined by the hood **12** or may be provided as a component that is connected to the hood **12**.

A portion **84** of the ejected suppression medium **38** from the ejection nozzle **34** that forms a fluid barrier may flow from the ejection nozzle **34** towards and through the return inlet **70**. The portion **84** of the ejected suppression medium **38** that enters the return inlet **70** may flow through the return duct **56** to the duct **54** and to the fluid passageway **52**. The portion **84** of the ejected suppression medium **38** may continue to be recycled and returned through the fluid return **50** while the suppression medium **38** is being delivered to the hazard volume **20** by at least one of the ejection nozzle **34** and/or the dispersion nozzle **36**.

Referring to FIGS. 1A, 1B, 2, and 3, the valve assembly **32** is arranged to control the release of the suppression medium **38** from the container **30** to the ejection nozzle **34** and the dispersion nozzle **36**, responsive to a thermal event or a fire hazard **86** within the hazard volume **20**. The suppression medium **38** may be released into the conduit **40** and directed towards the ejection nozzle **34** and the dispersion nozzle **36** through their respective conduit branches (e.g. the first branch **44** and the second branch **46**).

The ejection nozzle **34** may be provided with or may be defined by the hood **12**, as shown in FIGS. 1A, 2, and 3. The ejection nozzle **34** may be positioned between the non-hazard volume **22** and the hazard volume **20** while being spaced apart from the workstation **14**. The ejection nozzle **34** may be generally aligned with the edge **80** of the workstation **14**. The ejection nozzle **34** may be provided or positioned proximate the edge **80** of the workstation **14**, as shown in FIG. 1B, positioned near the base of the fire hazard **86**, or within a wall.

The ejection nozzle 34 may be arranged as an elongated opening that extends along an edge of the hood 12 or the workstation 14. The ejection nozzle 34 may be arranged as a plurality of fluid openings or fluid ports that may extend at least partially across an edge of the hood 12 or the workstation 14. The ejection nozzle 34 may be arranged as a single ejection nozzle or a plurality of ejection nozzles that at least partially extend from the hood 12 or the workstation 14.

The ejection nozzle 34 is arranged to eject the suppression medium 38 from the hood 12 towards the edge 80 of the workstation 14 to form a fluid curtain or a fluid barrier 90 that extends from the hood 12 towards the workstation 14, as shown in FIGS. 1A, 2, and 3. The ejection nozzle 34 may be arranged to eject the fluid and/or the suppression medium 38 from the edge 80 of the workstation 14 towards the front edge 60 of the hood 12 to form the fluid barrier 90 that extends from the workstation 14 towards the hood 12, as shown in FIG. 1B. The fluid barrier 90 may be formed as a generally vertical curtain of laminar flow of the fluid and/or the suppression medium 38 that is disposed between and isolates the hazard volume 20 from the non-hazard volume 22 to contain or isolate the thermal event or fire hazard 86 present within the hazard volume 20 from the non-hazard volume 22.

The fluid and/or the suppression medium 38 may be ejected by the ejection nozzle 34 at a first flow rate. The first flow rate may be pronounced such that the fluid barrier 90 inhibits a flow 92 of oxygen or other oxidizers from the non-hazard volume 22 from entering into the hazard volume 20 and inhibits a flow 94 of the fluid and/or the suppression medium 38 from within the hazard volume 20 from entering into the non-hazard volume 22.

Referring to FIG. 2, a deflector 100 may be provided to aid in directing or deflecting at least a portion of the fluid and/or the suppression medium 38 that forms the fluid barrier 90 towards the hazard volume 20/the fire hazard 86 and away from the non-hazard volume 22. The deflector 100 is spaced apart from and is proximately aligned with the ejection nozzle 34. The deflector 100 may be operatively connected to the workstation 14 and may be disposed proximate the edge 80 of the workstation 14. In at least one embodiment, the deflector 100 may be operatively connected to the hood 12 and may be arranged to direct the ejected suppression medium 38 from the ejection nozzle 34 disposed on the workstation 14 that forms the fluid barrier 90 towards the fire hazard 86 and away from the non-hazard volume 22.

The deflector 100 may include an extension 102 that extends from the edge 80 of the workstation 14 and a deflection surface 104. The deflection surface 104 may be defined by the extension 102 or may extend from the extension 102 towards the edge 80 of the workstation 14. The deflection surface 104 may be an arcuate surface or an angled surface that is arranged to deflect the suppression medium 38 that forms the fluid barrier 90 towards the fire hazard 86 or generally within the hazard volume 20.

Referring to FIGS. 1-3, the dispersion nozzle 36 is spaced apart from the ejection nozzle 34. The dispersion nozzle 36 is disposed proximate or within the hazard volume 20 and extends towards the workstation 14. The dispersion nozzle 36 is arranged to disperse the fluid and/or the suppression medium 38 within the hazard volume 20 and towards the workstation 14 at a second flow rate. The second flow rate may be less than the first flow rate of the first flow rate and/or the suppression medium 38 ejected from the ejection nozzle 34.

In at least one embodiment, the first flow rate of the fluid and/or the suppression medium 38 from the ejection nozzle 34 and/or the second flow rate of the fluid and/or the suppression medium 38 from the dispersion nozzle 36 may be independently variable. The respective flow rates may be varied by additional valve assemblies that are fluidly connected to the first branch 44 and the second branch 46 or by the valve assembly 32.

The ejection of the fluid and/or the suppression medium 38 through the ejection nozzle 34 and the dispersion of the fluid and/or the suppression medium 38 through the dispersion nozzle 36 may occur substantially simultaneously responsive to detection of the thermal event or fire hazard 86 within the hazard volume 20, by a sensor or thermal detection element that may be in communication with valve assembly 32 of the fire suppression and isolation system 10.

The containment or isolation of the hazard volume 20 from the non-hazard volume 22 by the fire suppression and isolation system 10 may present benefits such as: provide a cleaner method of fire suppression that may not create collateral damage to the hazard volume 20 or non-hazard volume 22; reduce cleanup time required after a discharge from the fire suppression and isolation system 10; reduce a duration of a shutdown of the workstation 14 after suppression or extinguishing of a fire hazard 86; containing the suppression medium 38 within the hazard volume 20; independently controlling the atmosphere about a fire hazard 86 by isolating hazard volume 20 containing the fire hazard 86 from the non-hazard volume 22; and controlling an amount of the suppression medium 38 present within the hazard volume 20.

The term "about" is intended to include the degree of error associated with measurement of the particular quantity based upon the equipment available at the time of filing the application.

The terminology used herein is for the purpose of describing particular embodiments only and is not intended to be limiting of the present disclosure. As used herein, the singular forms "a", "an" and "the" are intended to include 40 the plural forms as well, unless the context clearly indicates otherwise. It will be further understood that the terms "comprises" and/or "comprising," when used in this specification, specify the presence of stated features, integers, steps, operations, elements, and/or components, but do not 45 preclude the presence or addition of one or more other features, integers, steps, operations, element components, and/or groups thereof.

While the present disclosure has been described with reference to an exemplary embodiment or embodiments, it will be understood by those skilled in the art that various changes may be made and equivalents may be substituted for elements thereof without departing from the scope of the present disclosure. In addition, many modifications may be made to adapt a particular situation or material to the 55 teachings of the present disclosure without departing from the essential scope thereof. Therefore, it is intended that the present disclosure not be limited to the particular embodiment disclosed as the best mode contemplated for carrying out this present disclosure, but that the present disclosure will include all embodiments falling within the scope of the 60 claims.

What is claimed is:

1. A fire suppression and isolation system, comprising:
a hood;
a workstation including a back wall, the workstation including a heat generating appliance, the heat generating appliance disposed underneath the hood and in

front of the back wall so as to be partially enclosed by the hood and the back wall, a hazard volume being located between the work station and the hood, a non-hazard volume being outside of the hood and workstation, the heat generating appliance being one of a cooktop, a broiler, a grill, a deep fat fryer, and a weld station
 5 an ejection nozzle disposed on a distal end of the hood and positioned between the non-hazard volume and the hazard volume;
 a dispersion nozzle spaced apart from the ejection nozzle and disposed within the hazard volume; and
 10 a valve assembly arranged to control a release of a suppression medium from a container to the ejection nozzle and the dispersion nozzle, responsive to a thermal event, such that the suppression medium ejected from the ejection nozzle defines a fluid barrier that is disposed between the non-hazard volume and the hazard volume;
 a fluid return having a return inlet that is spaced apart from and is axially aligned with the ejection nozzle, the return inlet fluidly coupled to a passageway that extends along the back wall and is fluidly coupled to the ejection nozzle so as to recycle so as to recycle the suppression medium; and
 15 wherein the ejection nozzle is arranged to eject the suppression medium at a first flow rate; and
 the dispersion nozzle is arranged to disperse the suppression medium at a second flow rate that is less than the first flow rate.
 20 2. The fire suppression and isolation system of claim 1, wherein the suppression medium is at least one of water, air, an inert gas, and a clean agent.

- 25 3. The fire suppression and isolation system of claim 1, wherein the dispersion nozzle is arranged to disperse the suppression medium within the hazard volume.
 4. The fire suppression and isolation system of claim 1, wherein the ejection nozzle is at least partially disposed on the workstation.
 5. The fire suppression and isolation system of claim 1, further comprising a deflector that is spaced apart from and is proximately aligned with the ejection nozzle, the deflector being arranged to deflect at least a portion of the fluid barrier towards the hazard volume.
 10 6. The fire suppression and isolation system of claim 1, wherein the ejection nozzle is at least partially disposed in a hood.
 15 7. The fire suppression and isolation system of claim 1, wherein the fluid return is at least partially defined by the workstation.
 8. The fire suppression and isolation system of claim 1, wherein the ejection nozzle is arranged to eject the suppression medium towards at least one of an edge of the workstation and a front edge of the hood.
 20 9. The fire suppression and isolation system of claim 1, wherein the fluid barrier is formed as a curtain of laminar flow of the suppression medium.
 10. The fire suppression and isolation system of claim 1, wherein the dispersion nozzle is arranged to disperse the suppression medium towards the workstation.
 11. The fire suppression and isolation system of claim 10, wherein the fluid barrier is arranged to inhibit the suppression medium from flowing into the non-hazard volume.
 30 12. The fire suppression and isolation system of claim 1, wherein the fluid return is arranged to receive at least a portion of the suppression medium ejected from the ejection nozzle.
